RAILROAD CROSSING STRUCTURE

Herbert E. White and Thomas E. McLaughlin,
Cleveland, Ohio, assignors to Truscon Steel
Company, Youngstown, Ohio, a corporation of
Michigan

Application September 26, 1930
Serial No. 484,673

16 Claims. (Cl. 238—8)

The object of the present invention is to provide a railroad crossing structure that has peculiarly efficient wear and weather-resisting qualities, and involves units or parts which can be readily manufactured and easily assembled.

An embodiment of the invention that is at present considered the preferable one, is illustrated in the accompanying drawings, wherein:—

Figure 1 is a top plan view of a section of a railway track, showing the crossing structure between the rails.

Figure 2 is a longitudinal sectional view on the line 2—2 of Figure 1.

Figure 3 is a cross sectional view on the line 3—3 of Figures 1 and 2.

Figure 4 is a detail sectional view on the line 4—4 of Figure 1.

Figure 5 is a bottom plan view of one of the tread bars.

Figure 6 is a top plan view of a portion of the same.

Figure 7 is a sectional view on the line 7—7 of Figure 5.

Figure 8 is a plan view of one of the guard plates.

Figure 9 is an end elevation of the same looking in the direction of the arrow A of Figure 8.

Figure 10 is a plan view of one of the carrier and retaining bars.

Figure 11 is a side elevation of the same.

Figure 12 is a cross sectional view on an enlarged scale and on the line 12—12 of Figure 11.

Figure 13 is a plan view of one of the associated carrier bars.

Figure 14 is a side elevation of the same.

Figure 15 is a cross sectional view on an enlarged scale and on the line 15—15 of Figure 14.

In the embodiment disclosed, a section of a standard railway is illustrated, comprising the

ties or sleepers 16 supporting the rails 17. At the crossing the ties have mounted thereon carrier bars.

These bars are of channeled formation, and as shown, are of two types. The bars of one set are designated generally by the reference nu-

meral 18, and one is shown in detail in Figures 13,

14 and 15. As therein shown, the bar is of channeled formation, comprising a bottom wall 19 and upstanding side walls 20, the latter having in-

turned bearing flanges 21. Holes 22 through the

central portion of the bottom wall 19, are adapted to receive spikes 23 or other suitable fasteners by

which the bars 18 are secured to the ties, these spikes being readily driven and accessible through

the space between the inner edges of the flanges

55 21.

The said bars 18 are placed on every second tie at the crossing, and on the intermediate ties are located other carrier bars 24. One of these bars is shown in detail in Figures 10, 11 and 12. It is of metal channeled formation, comprising a top wall 25 and depending side walls 26, the latter having along their lower edges in-turned flanges 27 constituting the supporting feet. The top wall 25 has upset from the material thereof sets of outstanding ears or lips 28, the intermediate portions of which are preferably depressed, as shown at 29. These carrier bars 24 are secured in place by spikes or other fasteners 30 driven through openings 31 in the top walls and entering the ties on which said carrier bars are placed.

Supported on the two sets of carrier bars 18 and 24 transversely thereof and therefore longitudinally of the rails and between said rails, are what may be termed tread or roadway bars. These are designated generally 31. The detail structure of one of these bars is shown in Figures 5, 6 and 7. Each is of channel formation, and consists of a top or bearing wall 32, which may be suitably roughened on its upper face, as illustrated in part at 33 in Figure 6, and also in Figure 7. Depending from the side edges of this top wall 32 are side supporting walls 34 terminating at their lower ends in in-turned supporting flanges 35 that constitute feet which rest upon the bars 18 and 24. It will be noted by reference to Figures 5 and 7 that the flanges 35 are cut away at intervals and as shown at 36, the length of the spaces thereby formed being slightly greater than the length of the lips 28 of the supporting bars 24. These lips 28 are elevated sufficiently above the top wall 25 of the bars 24 to permit the sections of the flanges 35 to pass beneath said lips, as shown in Figure 3.

It will be evident then that if the carrier bars 18 and 24 are secured on the ties 16, the tread bars 31 can be placed side by side thereon, the lips 28 entering through the spaces 36. The tread bars then have only to be moved a short distance longitudinally to cause them to be interlocked or held by said lips 28. A roadway across the space between the rails is thus produced and held assembled.

In order to prevent any low hanging elements of the cars engaging the ends of the tread bars and perhaps tearing them loose or otherwise injuring the crossing and to prevent any longitudinal displacement of said tread bars, guard plates 37 are located at the ends of the crossing. These plates are of suitable flat metal with their main

100

105

110

portions upwardly inclined and having outer horizontal flanges 38 that rest upon the adjacent tie to which they are fastened by suitable bolts or spikes 39. The upper end portion of each plate 5 has a downturned flange 40 (see Figure 9), and this flange is provided with outturned lugs 41 that enter the open ends of the tread bars.

It will be evident that this is a structure that can be made of units of formed metal and that 10 these units may be readily placed in position and assembled into a crossing or like structure. When assembled the parts are all effectively interlocked so that they will retain their position. Being of metal they will withstand weather conditions and 15 traffic more successfully than ordinary wood plank or the like usually employed for crossings.

From the foregoing, it is thought that the construction, operation and many advantages of the herein described invention will be apparent to 20 those skilled in the art without further description, and it will be understood that various changes in the size, shape, proportion and minor details of construction may be resorted to without departing from the spirit or sacrificing any 25 of the advantages of the invention.

What we claim, is:

1. In a railroad crossing, the combination with the ties and rails supported thereon, of a set of carrier bars of channeled formation mounted on 30 the ties between the rails, and a set of elongated metal channel bars mounted on the carrier bars and extending longitudinally of the rails.

2. In a railroad crossing, the combination with the ties and rails supported thereon, of a set of carrier bars of channeled formation mounted on 35 the ties between the rails, and a set of elongated metal channel bars mounted on the carrier bars and extending longitudinally of the rails, said channel bars being interlocked with the carrier bars.

3. In a railroad crossing, the combination with the ties and rails supported thereon, of a set of carrier bars of channeled formation mounted on 40 the ties between the rails, and a set of elongated metal channel bars mounted on the carrier bars and extending longitudinally of the rails, certain of said bars having retaining lips and other of the bars having portions engaged by the lips.

4. In a railroad crossing, the combination with the ties and rails supported thereon, of a set of carrier bars of channeled formation mounted on 45 the ties between the rails, and a set of elongated metal channel bars mounted on the carrier bars and extending longitudinally of the rails, the carrier bars having offset retaining lips and the other bars having flanges engaged beneath the lips.

5. In a railroad crossing, the combination with the ties and rails supported thereon, of a set of carrier bars of channeled formation mounted on 50 the ties between the rails and having upstanding offset retaining lips, and a set of channel bars seated on the carrier bars and having side walls provided with longitudinal offset flanges engaged beneath the lips.

6. In a railroad crossing, the combination with the ties and rails supported thereon, of a set of carrier bars of channeled formation mounted on 55 the ties between the rails and having upstanding offset retaining lips, and a set of channel bars seated on the carrier bars and having side walls provided with longitudinal offset flanges engaged beneath the lips, said flanges having cut away 75 portions adjacent the lips to permit the passage

of said lips on a limited longitudinal movement of the bars carrying said flanges.

7. In a railroad crossing, the combination with ties and rails supported thereon, of channel bars laid on the ties between the rails, certain of said channel bars having upset and offset retaining lips, and tread bars of channel formation laid on the carrier bars longitudinally of the rails and comprising top bearing walls, and side walls, said side walls having inturned flanges that are overlaid by the lips. 80

8. In a railroad crossing, the combination with ties and rails supported thereon, of channel bars laid on the ties between the rails, certain of said channel bars having upset and offset retaining lips, and tread bars of channel formation laid on the carrier bars longitudinally of the rails and comprising top bearing walls, and side walls, said side walls having inturned flanges that are overlaid by the lips, said flanges having portions 85 cut away between the lips and adapted to let said lips pass the flanges when the tread bars are moved longitudinally a limited distance. 90

9. In a railroad crossing, the combination with the ties and rails carried thereby, of a plurality 100 of formed metal bars located side by side between and longitudinally of the rails, and a guard plate at the ends of the bars having an interlocking engagement with a plurality of the bars.

10. In a railroad crossing, the combination with 105 the ties and rails carried thereby, of a plurality of formed open ended metal hollow bars located between and longitudinally of the rails, and a guard plate at the ends of the bars extending across a plurality thereof and having portions 110 engaging in the open ends of a plurality of said bars.

11. In a railroad crossing, the combination with the ties and rails carried thereby, of a plurality 115 of formed metal bars located side by side between and longitudinally of the rails, and a guard plate at the ends of the bars having a flange at the ends of the bars such flange having outstanding lugs that engage in the open ends of certain of said bars. 120

12. In a railway grade crossing having rails and ties supporting said rails, crossing elements of less depth than the depth of said rails, and sheet metal spacing members for supporting said crossing elements above said ties to maintain 125 the upper surface of said crossing elements substantially flush with the top of said rails.

13. In a railway grade crossing having rails and ties supporting said rails, crossing elements of less depth than the depth of said rails, sheet 130 metal spacing members secured to said ties and each having an upper web and side walls for supporting said crossing elements above said ties to maintain the upper surface of said crossing elements substantially flush with the top of said 135 rails, and means on said spacing members for securing said crossing elements in correlated juxtaposition.

14. In a railway grade crossing having rails and ties supporting said rails, crossing elements of 140 less depth than the depth of said rails, sheet metal spacing members secured to said ties for supporting said crossing elements above said ties to maintain the upper surface of said crossing elements substantially flush with the top of said 145 rails, said members having an upper web and side walls, and ears struck up from the upper web of said spacing members for securing said crossing elements in correlated juxtaposition.

15. In a railway grade crossing having rails 150

- and ties supporting said rails, crossing elements of less depth than the depth of said rails, and sheet metal spacing members for supporting said crossing elements above said ties to maintain the upper surface of said crossing elements substantially flush with the top of said rails, each of said members having an upper web and side walls, the lower edge portions of said side walls being bent at an angle thereto into substantially 80
- 5 a horizontal plane to provide bearing surfaces for supporting the spacing members and to provide means for securing the same to the ties. 85
- 10 16. In a railway grade crossing having rails and ties supporting said rails, crossing elements 15

of less depth than the depth of said rails, and sheet metal spacing members for supporting said crossing elements above said ties to maintain the upper surface of said crossing elements substantially flush with the top of said rails, each of said members having an upper web and side walls, the edge portions of said side walls being bent inwardly toward each other into a common horizontal plane to provide bearing surfaces for supporting the spacing members and also to provide means for securing the same to the ties. 90
